A Lockard.

By Geo. P. Kimmel Attorney

UNITED STATES PATENT OFFICE.

ALONZO LOCKARD, OF MASSILLON, OHIO.

GRAIN-SIEVE.

1,381,718.

Specification of Letters Patent. Patented June 14, 1921.

Application filed April 7, 1920. Serial No. 372,031.

To all whom it may concern:

Be it known that I, ALONZO LOCKARD, a citizen of the United States residing at Massillon, in the county of Stark and State 5 of Ohio, have invented certain new and useful Improvements in Grain-Sieves, of which the following is a specification.

This invention relates to the grain screens for threshing machines, fanning mills, and 10 like types of machines, and has for one of its objects to provide a simply constructed device of this character comprising superimposed slidably disposed members each with a plurality of apertures relatively small and 15 a plurality of apertures relatively large, so that when the screen members are adjusted to one position all of the smaller apertures will register and present a surface with all of the apertures of uniformly small size, 20 and when adjusted to another position, the major portion of the smaller apertures will register and all of the larger apertures will likewise register.

With these and other objects in view, the 25 invention consists in certain novel features of construction as hereinafter shown and described and then specifically pointed out in the claim, and in the drawings illustrative of the preferred embodiment of the invention,

Figure 1 is a top plan view with the coacting screen members so arranged that the smaller apertures of both screen members register and the larger apertures of one 35 screen member are disposed opposite certain of the smaller apertures of the other screen member.

Fig. 2 is a bottom plan view with the screen members so arranged that the major 40 portion of the smaller apertures of both screens register and the larger apertures of both screens are likewise arranged in registering position.

Fig. 3 is a section on the line 3—3 of Fig. 1. 45 The improved device comprises coacting screen members 10 and 11 superimposed, and formed of sheet metal of the usual grade and provided with the usual uniformly sized relatively small apertures 12 and 13 and a 50 plurality of relatively large apertures 14 and 15. The apertures 12 and 13 are uniformly spaced so that they register when the screen members are disposed in one position, as shown in Fig. 1. The larger apertures are 55 formed by cutting out certain of the "lands" or material between the smaller

apertures at regular intervals, the center of each larger aperture being the center of one of the smaller apertures, and the margins of the larger apertures cutting substantially 60 across the centers of the surrounding smaller apertures, as illustrated more clearly in Fig. 1.

The larger apertures are uniformly spaced as shown so that when the movable screen 65 member is adjusted to one position, the larger apertures will be disposed opposite certain of the smaller apertures of the other or stationary screen member; hence the smaller apertures only will be presented to 70 the material flowing thereover; and then when the movable screen member is adjusted to its other position, the larger apertures of both screen members will be disposed in registering position, and present a plurality of 75 relatively large openings or apertures entirely through both screen members, while at the same time the smaller apertures filling the major area of the screen members will still remain in registering position. 80

There is thus provided a simply constructed device wherein a screen having uniformly spaced relatively small apertures is provided, and a screen having a relatively large number of small apertures and a relatively small 85 number of larger apertures commingled with the smaller apertures.

Thus when fine material is to be "screened," the screen members will be so arranged that small apertures only are presented, and when 90 coarser material is to be "screened," the combined large and small apertures will be presented.

The superimposed screen members may be supported and operated in any suitable manner, but for the purpose of illustration a suitable frame 16 is provided to which the screen member 10 is secured in any suitable manner and with combined supporting and material guiding cleats 17 attached to the screen above 100 the side rails of the frame.

The other screen member 11 is also attached to a frame 18 fitted within the outer frame 16 and shorter than the same so that it can be moved endwise a sufficient distance 105 to provide for the change of position of the screen members as before described. The inner frame 18 is provided with a central rail 19 and the outer frame 16 provided with corner plates 20 to slidably support the 110 inner frame 18.

Pivoted at 21 to one member of the frame

16, is a bell crank lever 22, and pivoted at 23 to one arm of the lever is a link 24, the latter pivoted at 25 to the center rail 19 of the inner frame. The other arm of the 5 bell crank lever constitutes a handle by which the same may be operated, to move the inner frame 18 and the screen member 11 carried thereby into either one of its two positions.

10 The improved device is simple in construction, can be inexpensively manufactured, and adapted without material structural change, to screens having various sizes of 15 apertures and to screens employed in any of the various machines using screens for any purpose.

The preferred embodiment of the invention is disclosed in the drawings and set forth in the specifications, but it will be understood 20 that any modification within the scope of the claim may be made in the construction with-

out departing from the principle of the invention or sacrificing any of its advantages.

I claim:

A screen consisting of a pair of screen 25 plates each having therein a plurality of small circular apertures and a plurality of larger circular apertures, the edges of the larger apertures being defined by a plurality of substantially semi-circular notches 30 corresponding in curvature to said smaller apertures, so that the notches of said larger apertures in said plates may be made to coincide when said screen plates are in one relative position, and said small apertures 35 made to coincide with said notches when said screen plates are in another relative position.

In testimony whereof, I affix my signature hereto.

ALONZO LOCKARD.
